Primary Examiner—Wallace R. Burke*Assistant Examiner*—M. Brown*Attorney, Agent, or Firm*—Robert A. Seemann**[57] CLAIM**

The ornamental design for a document holder for bicycles, as shown and described.

DESCRIPTION

FIG. 1 is a front view of a document holder showing my new design;

FIG. 2 is a left side view of the document holder;

FIG. 3 is a top view of the document holder rotated from FIG. 2;

FIG. 4 is a bottom view of the document holder with the clip rotated 180 degrees on the strap;

FIG. 5 is a rear view of the document holder; and,

FIG. 6 is a perspective view of the document holder, the broken lines are shown for illustrative purposes only and form no part of the claimed design.

FIG. 1

FIG. 2

FIG. 3

FIG. 4

FIG. 5

FIG. 6
